UNITED STATES PATENT OFFICE.

GEORGE STONE, OF NORTH ANDOVER, MASSACHUSETTS, ASSIGNOR OF ONE-HALF TO
M. T. STEVENS & SONS COMPANY, OF NORTH ANDOVER, MASSACHUSETTS, A COR-
PORATION OF MASSACHUSETTS.

DRYING MACHINE.

1,421,856.

Specification of Letters Patent. Patented July 4, 1922.

Application filed December 15, 1921. Serial No. 522,491.

To all whom it may concern:

Be it known that I, GEORGE STONE, a citizen of the United States, residing at North Andover, in the county of Essex and State of Massachusetts, have invented new and useful Improvements in Drying Machines, of which the following is a specification.

This invention relates to machines for drying material, such as washed wool, by passing the same in a sinuous course, and in a plurality of horizontal stretches through a casing, from the upper to the lower portion of the latter, and forcing hot air through the horizontal stretches while they are being conveyed, the said stretches being conveyed by horizontal rows of rolls arranged at different heights, and spaced apart to provide air passages through which hot air is forced between the rolls, the arrangement being such that each row above the lowest, drops the material on to a lower row, the rolls of each row rotating in unison, in a direction opposite that of the next row.

One object of the invention is to provide means for conducting independent currents of hot air under the rolls of each row, and causing a forcible upward discharge of air between the rolls in such manner as to not only pass through and dry the conveyed material, but also to lift the same and prevent it from clinging to the rolls and clogging the latter.

Another object is to enable hot air that has been discharged between the rolls of one row, and has once performed its function, to be again utilized by cooperating with the rolls of another row or rows, and to be repeatedly heated without being discharged from the machine, thus economizing heat.

Another object is to provide means for highly heating the air supplied to the lower rows of the series, so that foreign matter in the material conveyed by said rows may be carbonized.

Another object is to provide means for crushing carbonized matter delivered by the lower row of rolls.

The invention is embodied in the improvements hereinafter described and claimed.

Of the accompanying drawings forming a part of this specification,—

Figure 1 is a side elevation of a drying machine embodying the invention.

Figure 2 is a fragmentary side view illustrating means for rotating the rolls. 55

Figure 3 is a section on line 3—3 of Figure 2.

Figure 4 is a longitudinal vertical sectional view of the machine.

Figure 5 is an enlargement of a portion of Figure 4. 60

Figure 6 is a half section on line 6—6 of Figure 1.

Figure 7 is a half section on line 7—7 of Figure 1. 65

Figure 8 is an enlarged section on line 8—8 of Figure 1.

Figure 9 is an enlargement of a portion of Figure 1.

Figure 10 is a top plan view, showing portions of the crushing rolls shown by dotted lines in Figure 9, and the mechanism for driving the lower rolls. 70

Figure 11 is a view similar to Figure 9, omitting the mechanism for driving the lower crushing rolls. 75

Figure 12 is a section on line 12—12 of Figure 10.

The same reference characters indicate the same parts in all of the figures. 80

The casing 12 of the machine, which may be of any suitable construction, is formed to house the various rolls and air conductors hereinafter described, and is provided at its upper portion with an inlet 13, to which material to be dried is fed by any suitable means. As shown by Figures 1 and 4, the feeding means may include an endless conveyor 15. Within the casing is a plurality of horizontal rows of rolls 16, the rolls of each row being spaced apart, as best shown by Figure 5, to form air spaces 17 between the rolls, and rotated in unison to convey material from end to end of the row. Each row above the lowest is arranged to drop the material conveyed by it on to a lower row, and the rolls of each row are rotated in a direction opposite that of the rolls of the next row, so that the rolls are adapted to conduct the material in a sinuous course, and in horizontal stretches from a point under the inlet 13 to an outlet 18 at the lower portion of the casing. The material is guided on to the receiving ends of the rows by fixed guides or deflectors 19. Any suitable mechanism may be provided for rotating the rolls, such as 95 100 105

sprocket wheels 20 (Figures 2, 3, and 8), fixed to trunnions 21, which are fixed to the rolls, the latter being preferably tubular, as shown by Figure 8, and sprocket chains 22, portions of which are shown in detail by Figures 2 and 3, the chains being shown conventionally and in dotted lines by Figure 1.

The general construction and arrangement thus far described is well known, and does not of itself form a part of my invention. I do not, therefore, fully show the sprocket chains, nor the mechanism that drives the same, it being sufficient to say that the chains may be driven by power imparted through a driving-shaft, indicated at 23 (Figure 1), horizontal stretches of the chains being engaged with the sprocket wheels on the rolls to simultaneously rotate the rolls of each row in the directions described.

In accordance with my invention, I provide air forcing and heating apparatus at one end of the casing 12, and locate separate air conductors under the rows of rolls, communicating with said apparatus, and adapted independently to conduct air from the said apparatus under the rolls of each row, and to exhaust or discharge the conducted air upwardly through the spaces 17, between the rolls and into air chambers above the rolls. The air thus exhausted acts on the material in transit on the rolls, to not only dry the material by passing through it, but also to lift the material sufficiently to prevent it from clinging to the rolls, and therefore from being carried between and clogging the rolls, said independent conductors being the essence of the invention.

Each conductor is preferably provided by locating in the casing below each row of rolls a horizontal sheet metal bottom plate 24, extending from side to side of the casing, as indicated by Figures 6 and 7, and extending lengthwise of the casing from end to end of the series of rolls above it, as shown by Figure 4, one end of said plate being turned up into close proximity to the roll 16, at the delivery end of the row, to form a transverse end wall 25. The plate 24, the end wall 25, portions of the sides of the casing 12, and the row of rolls constitute a box which has an inlet communicating with the air-forcing and heating apparatus, and a multiplicity of outlets provided by the spaces 17 between the rolls. Air forced under pressure into said box is forcibly exhausted or discharged through said spaces into material conveyed by the rolls, and lifts said material while drying it. The box thus constituted, and the rolls associated therewith, may be called a material-drying and conveying unit. The machine may include any desired number of units, five being here shown.

An air chamber is provided above each of

said units, to receive the air exhausted therefrom, said chambers being designated respectively 1, 2, 3, 4 and 5, at the right hand end portion of Figure 4, each chamber having an air outlet. The air exhausted into the highest chamber 1 is heavily charged with moisture, and has an air outlet 27 (Figure 4) arranged to discharge the moist air into the atmosphere. The outlets of other air chambers may be provided by by-passes arranged to conduct the air that has performed its function in one unit to a lower portion of the machine, so that air that is not objectionably moist, and contains a considerable percentage of heat, may be again utilized without being discharged from the machine.

Referring to Figures 1, 4, 6, and 7, it will be seen that the air chamber 2 is connected by an angular by-pass 28 with a horizontal return flue or passage 29, located between the third and fourth units, and that a branch 28^a of said by-pass is connected with the air chamber 3. There are preferably two of said by-passes, one at each side of the casing 12. The return flue 29 communicates with the air-forcing and heating apparatus, which is organized as hereinafter described, to exert suction on air in said flue, so that air is drawn from the chambers 2 and 3, and through the return flue to the said apparatus, where it is additionally heated, and from which it is forced to units above the said flue, as indicated by some of the arrows in Figure 4.

I have shown two units below the flue 29, one exhausting into the chamber 4, and the other into the chamber 5. The air chamber 4 is connected by a by-pass 31, with a lower horizontal return flue 32, located below the bottom unit, and by a branch 31^a of said by-pass with the air chamber 5. The return flue 32 communicates with the air-forcing and heating apparatus, which exerts suction on air in said flue, so that air is drawn from the chambers 4 and 5, and through the return flue 32 to the said apparatus, where it is additionally heated, and from which it is forced into the air conductor of the lowest unit, as indicated by arrows in Figure 4.

The air-forcing and heating apparatus is preferably arranged to force air directly into the air conductor of the unit immediately under the chamber 1, through an inlet 34 (Figure 4), and into the air conductor of the unit immediately under the chamber 3, through an outlet 35. A portion of the air forced by said apparatus into the conductor of the highest unit may enter the conductor of the next lower unit through a by-pass 36 (Figures 4 and 6), the air exhausted from this unit into the chamber 2 being withdrawn therefrom through the by-pass 28, as above described. Air is preferably forced by said apparatus into the air conductor of the lowest unit immediately

under the chamber 5, through an inlet 37 (Figure 4), and is exhausted between the rolls of said unit into the chamber 5, from whence it is drawn to the return flue 32, as 5 above described. A portion of the air forced by said apparatus into the conductor of the lowest unit, may enter the chamber of the next higher unit through a by-pass 36 (Figures 4 and 7), the air exhausted from 10 this unit into the chamber 4 being withdrawn therefrom, and returned to the air-forcing and heating apparatus.

When the machine is used for drying wool containing burrs, and other vegetable foreign matter capable of being carbonized, I 15 arrange the conveying and drying units in two groups, one above and the other below the return flue 29. I also provide an air-forcing and heating apparatus, composed of 20 two separate sections, one which is called the primary section, and is associated with the units of the upper group, and the other, which is called the secondary section, with the units of the lower group.

25 As shown by Figure 4, the primary section includes an upper box or casing 38, and the secondary section includes a lower box or casing 39. In each casing is a fan adapted to draw air from some of the air chambers, and force the same into the air conductors of the corresponding units. Any suitable type of fan may be employed. I show only the casings 41 of said fans, each fan having an intake through which air exhausted from some of the units enters the casing, and an outlet through which air is forced through a heater and back to the units. The fan in the casing 38 forces air between the pipes or coils of a steam heated 30 radiator 42, located in said casing between the fan and the inlets 34 and 35, and draws exhausted air through the return flue 29. The fan in the secondary casing 39 forces air between the pipes or coils of a similar 35 radiator 43, located between said fan and the inlet 37, and draws exhausted air through the return flue 32.

It will now be seen that the fan in the primary casing 38 forces air through the 40 upper group of units, and that the exhausted hot or warm air from said units, excepting that discharged into the atmosphere at the outlet 27, is drawn back into the primary casing by said fan.

45 It will also be seen that air is rapidly circulated through the heater 43, the units of the secondary group and the return flue 32. A sufficiently high temperature is therefore maintained in the units of this group, to 50 carbonize foreign matter in the conveyed material.

At the delivery end of the lower row of rolls 16, is a crushing means adapted to pulverize the carbonized matter, the same being 55 embodied in a series of lower rolls 45, posi-

tively driven in unison with said lower rolls 16, and a series of vertically movable spring-pressed idle rolls 46. The material delivered by the lower rolls 16 passes between the rolls 45 and 46, and is subjected thereby to pressure sufficient to crush the carbonized material. The lower rolls 45 may be driven in unison by a suitable train of gears 48 (Figures 9, 10 and 11), to which power is applied through a driving pulley 49. The 70 crushing rolls are preferably located within the casing 12, and deliver the material through the outlet 18.

It is obvious that when material is to be dried without being carbonized, a smaller 80 number of units may be employed, the crushing means being omitted, and the air-forcing and heating apparatus being suitably modified.

The various by-passes may be provided 85 with clean-out openings or hand holes, closed by removable covers 50, as shown by Figure 1. The casing 12 may be provided with doorways, closed by doors 51. The perforated sheet-metal plates 52, shown by Figures 4, 6, and 7, in the chambers 2, 3, 4 and 5, are baffle-plates, which prevent the air discharged between the rolls 16 from taking the shortest possible path to the intakes of the several by-passes, so that the air lifts 95 the material on the rolls more effectively than would be the case if said baffle-plates were not present.

The perforated plates also intercept lint, or small fragments of material rising from 100 the rolls 16, and prevent the same from being conducted to the fans. Each perforated plate is preferably made in sections, which are loosely supported in the casing 12, and are removable through the said doorways, 105 when the doors 51 are opened, so that they may be readily cleaned. The said hand holes are intended to permit the removal from the by-passes of lint, and like matter accumulating therein.

110 The crushing rolls 45 and 46 are of larger diameter than the conveying rolls 16, and rotate at a greater surface velocity, the crushing rolls being preferably about nine inches in diameter, while the diameter of 115 the rolls 16 is preferably about three inches. To prevent the material from being drawn too rapidly from the delivering end of the lower row of rolls 16, by the crushing rolls, I provide a loose idle holding-back roll 55 120 (Figure 4), arranged to bear on material passing across the trough formed by the upper sides of the last two rolls 16 of the lower row. Said idle roll is preferably about six inches in diameter, and it acts to 125 partially hold back the material before it reaches the nip of the crushing rolls, by which it is first engaged, the fibers of the material being stretched between the holding-back roll and the nip of the first pair 130

of crushing rolls, so that it passes evenly, and not in bunches, between the crushing rolls.

It will be seen by reference to Figure 4, 5 that the air chamber 4 above the lower group of units, communicates through a space 56 with the air chamber 3 above the lower unit of the upper group, so that any surplus heated air that is not returned to the secondary section 39, of the air-forcing and heating apparatus, finds its way into the air chamber 3, and is utilized to dry material conveyed by the units of the upper group.

The casing sections 38 and 39 are closed 15 against the admission of air, excepting through the return or suction flues 29 and 32, and against the outflow of air, excepting through the outlets 34, 35 and 37, so that air pressure is maintained in said sections 20 by the fans. The intake of each fan casing may draw in a limited volume of outside air through orifices 40 (Figures 1 and 4) in addition to the air drawn through the return or suction flues, but the volume of outside 25 air thus drawn in should be considerably less than that drawn through said suction flues. When the machine is in operation, air is continuously forced through the primary heater 42, to the units and air chambers of the 30 upper group, the air exhausted from the highest unit escaping to the atmosphere, while the air exhausted from the other units of the upper group returns to the primary section 38, through the upper suction flue 35 29, and is again heated by the heater 42. Air is also continuously forced through the secondary heater 43 to the units and air chambers of the lower group, and returns to the secondary section 39 through the lower suction flue 32, and is again heated by the 40 heater 43, this air being at a fairly high temperature and relatively dry, so that any surplus thereof which may be caused to pass through the passage 56 (Figure 4), by pressure in the units and air chambers of the 45 lower group, is utilized to good advantage in the units and air chambers of the upper group.

It is obvious that the machine may be used 50 for drying any fibrous material such as wool, cotton, hair, etc.

I claim:

1. A drying-machine comprising a plurality of horizontal rows of conveying rolls 55 arranged at different heights, and adapted to conduct material in a sinuous course through the machine, the rolls of each row being separated by air spaces; air-forcing and heating apparatus; and independent air conductors 60 under said rows connected with said apparatus and adapted independently to conduct air under the rolls of each row, the conducted air being exhausted or discharged upwardly through said spaces into air chambers above the rolls, and utilized to both dry 65

and lift material in transit on the rolls, each row of rolls and the accompanying conductor constituting a conveying and drying unit.

2. A drying-machine comprising a plurality of horizontal rows of conveying rolls arranged at different heights, and adapted to conduct material in a sinuous course through the machine, the rolls of each row being separated by air spaces; air-forcing and heating apparatus; independent air conductors under said rows connected with said apparatus and adapted independently to conduct air under the rolls of each row, the conducted air being exhausted or discharged 70 upwardly through said spaces into air chambers above the rolls, and utilized to both dry and lift material in transit on the rolls, and means including by-passes communicating with some of said air chambers, whereby air 75 exhausted into an air chamber after performing its function is again utilized.

3. A drying and carbonizing-machine comprising a plurality of horizontal rows of conveying rolls arranged at different heights, 80 and adapted to conduct material in a sinuous course through the machine, the rolls of each row being separated by air spaces; air-forcing and heating apparatus; independent air conductors under said rows connected 85 with said apparatus and adapted independently to conduct air under the rolls of each row, the conducted air being exhausted or discharged upwardly through said spaces into air chambers above the rolls, and utilized to both dry and lift material in transit on the rolls, each row of rolls and the accompanying conductor constituting a conveying and drying unit, the said air forcing and heating apparatus being composed 90 of a primary section, communicating with an upper group of said units, and an air circulating secondary section, communicating with a lower group, the arrangement being 95 such that the lower group is heated to carbonize foreign matter in material conveyed by the rolls thereof, and crushing rolls at the delivering end of the lower row of rolls 100 for crushing such carbonized matter.

4. A drying and carbonizing-machine 105 substantially as specified by claim 3, comprising also means adapted and arranged to conduct surplus heated air exhausted from the lower group of units to the upper group.

5. A drying and carbonizing-machine 110 substantially as specified by claim 3, comprising also a return flue adapted to conduct heated air exhausted from the upper group of units to the said primary section.

6. A drying and carbonizing-machine 115 substantially as specified by claim 3, comprising also a return flue, adapted to conduct heated air exhausted from the lower group of units, to the said secondary section.

7. In a drying-machine, a conveying and drying unit comprising a horizontal row of conveying rolls, separated by air spaces, and rotated in unison to convey material from 5 end to end of the row, and enclosing means under said row forming, with the latter, a box having air outlets formed by the spaces between the rolls, said enclosing means being adapted to receive air, and to 10 exhaust the same through said outlets, so that material conveyed by the rolls is dried and also lifted to prevent it from clogging the rolls.

8. A drying-machine comprising a casing 15 having an inlet and an outlet, a plurality of drying and conveying units located at different heights, and arranged to cause material to pass in a sinuous course from the inlet to the outlet, each unit including a row 20 of rolls rotated in unison and spaced apart, and an air conductor under the rolls and adapted to discharge air upwardly between the rolls, the casing being provided with air chambers above said units into which 25 air forced between the rolls is exhausted; air-forcing and heating apparatus; and connections between said apparatus and the said air conductors and air chambers, the arrangement being such that air is forced independently through the heating units and 30 exhausted therefrom into the chambers.

9. A drying-machine comprising a casing having an inlet and an outlet, a plurality of drying and conveying units located at different heights, and arranged to cause material to pass in a sinuous course from the inlet to the outlet, each unit including a row of 35 rolls rotated in unison and spaced apart, and an air conductor under the rolls and adapted to discharge air upwardly between the rolls, the casing being provided with air chambers above said units, into which air forced between the rolls is exhausted; the highest air chamber being open to the atmosphere; air-forcing and heating apparatus; and circulating connections between 40 said apparatus, the said air conductors and the lower air chambers, the arrangement being such that air is circulated through the heating units and through the lower chambers, and reheated at said apparatus.

10. A drying-machine comprising a casing; air-forcing and heating apparatus; a plurality of horizontal conveying and dry-

ing units, arranged at different heights in 55 the casing and adapted to cause material to pass in a sinuous course through the casing, each unit including a row of spaced apart rolls, rotated in unison, and an independent air conductor under the row, and communicating with the spaces between the rolls, the casing being provided with a series of air chambers into which air is exhausted from 60 said units to dry and lift material in transit; and air-conducting connections between said 65 apparatus and the said conductors and air chambers, whereby air is forced from the apparatus into the conductors, and returned to the apparatus from the air chambers.

11. A drying-machine substantially as 70 specified by claim 10, the said air-forcing and heating apparatus being composed of a primary section and a secondary section, the said units being arranged in an upper group and a lower group, and the said air-conducting connections being organized to return air exhausted from units of the upper group to the said primary section, and to return air exhausted from the units of the lower group to the secondary section, to be heated by the 80 latter for the carbonization of matter carried by material in transit on the rolls of the lower units.

12. A drying and carbonizing-machine substantially as specified by claim 3, an air 85 chamber associated with the lower group of units, being connected with an air chamber associated with the upper group, so that surplus heated air that has been utilized in the lower group is again utilized in the upper 90 group.

13. A drying-machine substantially as specified by claim 2, comprising also perforated horizontal baffle-plates located in said air chambers, and adapted to prevent access 95 of lint and other like matter to the air-forcing apparatus.

14. A drying and carbonizing machine substantially as specified by claim 3, comprising also a loose holding-back roll associated with conveying rolls at the delivering end of the lowest unit, and adapted to cooperate with said crushing rolls in stretching and evening fibers of the material in transit.

In testimony whereof I have affixed my signature.

GEORGE STONE.
